United States Patent Office

Des. 186,175
Patented Sept. 22, 1959

186,175

CLIMBER SLIDE

Claude W. Ahrens, Grinnell, Iowa

Application May 11, 1959, Serial No. 55,874

Term of patent 14 years

(Cl. D34—5)

I claim:

The ornamental design for a climber slide, substantially as shown.
